(57) **CLAIM**

The ornamental design for surface mount for light receiving or emitting device, as shown and described.

DESCRIPTION

FIG. 1 is an upper, front, left perspective view of the surface mount for light receiving or emitting device;

FIG. 2 is a lower, rear, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines showing features of the surface mount for light receiving or emitting device form no part of the claimed design.
